UNITED STATES PATENT OFFICE.

SAMUEL S. AMDURSKY, OF ROCHESTER, NEW YORK, ASSIGNOR TO TAYLOR INSTRUMENT COMPANIES, OF ROCHESTER, NEW YORK, A CORPORATION OF NEW YORK.

FILTER.

Application filed September 25, 1924. Serial No. 739,948.

This invention relates to filters, and more particularly to the variety comprising detachable filtering cartridges, the chief object of the invention being to provide an improved device of this character constructed and arranged to facilitate the removal of the cartridge as well as the convenient replacement of the filtering material in the latter, together with various other features affording an efficient and convenient apparatus.

To these and other ends the invention resides in certain improvements and combinations of parts, all as will be hereinafter more fully described, the novel features being pointed out in the claims at the end of the specification.

In the drawings:

Fig. 1 is a sectional view through a filtering device embodying the present invention.

Fig. 2 is a top plan view of the same.

Fig. 3 is a view similar to Figure 2 with the container closure removed, and

Fig. 4 is a side elevation showing the container closure reversed and cooperating with the cartridge for unscrewing the same from the container.

Similar reference numerals throughout the several views indicate the same parts.

This invention, in the preferred embodiment herein disclosed by way of illustration, comprises a container 5 of the generally cylindrical form shown with an open top internally threaded as at 6. At the inner end of threaded portion 6 is a shoulder 7 in the present instance in the form of an annular flange providing a seat for the cartridge as hereafter described. The container is formed on opposite sides adjacent its top with outwardly projecting bosses 8 and 9 in which are threaded openings 10 and 11 for the reception of inlet and outlet connections, respectively. Inlet 10 is connected by a passageway 12 in boss 8 with the interior of casing 5 below shoulder 7, while outlet opening 11 is connected by a passageway 13 with the container interior above shoulder 7, so that the fluid entering the container through passageway 12 is directed through the cartridge carried on shoulder 7 and discharged through passageway 13.

The filtering cartridge comprises preferably a cylindrical sleeve 14 provided with threaded means adjacent one end for engage-

ment in the threaded open end 6 of the container to secure the cartridge on its seat in the latter in spaced relation with its walls as shown. In the present instance the upper end of sleeve 14 is formed with an outwardly projecting flange 15, the periphery of which is threaded for engagement with the container, the flange resting on a suitable gasket 16 on shoulder or seat 7 when the cartridge is screwed home as shown. It is apparent from this construction that the cartridge is securely supported in the container when in use and that it may be readily detached from the container by unscrewing it through the open container top.

The filtering cartridge is not only detachable as described but also preferably comprises detachable end portions for the purpose of readily inserting and replacing the filtering material. In the present instance this result is accomplished by spinning the lower end of the cartridge sleeve inwardly as at 17 to form a seat for a foraminous disk or end portion 18 on which the filtering material 19 is supported. The upper end of the cartridge sleeve is closed by a similar end portion 20 having upturned lugs 21 serving as handles for removing the same from the cartridge. When this has been done, the other end 18 may be readily pushed out through the top of the cartridge to carry with it the filtering material which may then be readily replaced together with the end portions in an obvious manner.

The open top of the container carries a closure which is advantageously constructed to serve also as a means for unscrewing the cartridge from the container. The closure is shown at 22 as seated on a gasket 23 on the rim of the container top with a projecting threaded plug 24 screwed into the container end. The closure is formed with an angular or square portion 25 by which it may be turned and this portion carries a rib 26 for cooperation with recesses 27 formed oppositely in the upper end of the cartridge sleeve. As indicated in Figure 4, the closure may be unscrewed from the container and reversed and the edge or rib 26 engaged in recesses 27, the closure plug 24 being provided with an angular portion 28 for turning the same to unscrew the cartridge and screw the same home against the seat in the container. The lower end of the latter is

equipped with a drain cock 29 of the usual or any suitable variety for the discharge of liquid collected in the same.

The operation of the filter and its parts has been explained in connection with the above description of its construction and it is apparent that the invention provides a simple and practical apparatus affording a combination and arrangement of parts by means of which the filtering cartridge may be quickly and conveniently removed and itself disassembled for the removal and replacement of the filtering material, with no other tool than an ordinary wrench for turning the container closure. In addition to such accessibility, the parts are adapted for manufacturing production and assembly at a comparatively low cost.

- I claim as my invention:
- 20 1. In a device of the class described, the combination of a container having an internally threaded open end and lateral inlet and outlet passages, a filtering cartridge having threaded means for detachably supporting the same in said container end between said passages, a closure for said container end, and means on said closure for unscrewing said threaded means and detaching said cartridge.
  - 25 2. In a device of the class described, the combination of a container having an internally threaded open end and inlet and outlet passages, a filtering cartridge having threaded means for detachably supporting

the same in said container end between said 35 passages, a closure threadedly engaged in said container end and provided on opposite sides with means for turning the same, and means on said closure for unscrewing said threaded cartridge means and detaching said 40 cartridge.

3. In a device of the class described, the combination of a container having an internally threaded open end and inlet and outlet 45 passages, a filtering cartridge comprising a sleeve threadedly supported in said container end and having detachable formous ends, a closure threadedly engaged in said container end and provided on opposite sides with means for turning the 50 same, and cooperating means on said cartridge and the outer side of said closure for unscrewing said cartridge for removal from the container.

4. In a device of the class described, the combination of a container having a cartridge-receiving space, an internally threaded opening and a shoulder intermediate the said opening and the said space defining a peripheral seat, a filtering cartridge having 60 at one end a flange for support on said seat, externally threaded to engage the threads of the opening, a closure for said opening, including means for screwing the cartridge into and out of operative position, and an 65 inlet and an outlet connected with the said space and the said opening, respectively.

SAMUEL S. AMDURSKY.
